UNITED STATES PATENT OFFICE.

GEORGE M. CULLEN, OF MILWAUKEE, WISCONSIN.

CANCELING-MACHINE.

1,214,898.

Specification of Letters Patent.

Patented Feb. 6, 1917.

Application filed July 23, 1914. Serial No. 852,679.

To all whom it may concern:

Be it known that I, GEORGE M. CULLEN, a citizen of the United States, residing at Milwaukee, in the county of Milwaukee and State of Wisconsin, have invented certain new and useful Improvements in Canceling-Machines, of which the following is a specification.

My invention relates to canceling machines and more particularly to that type used for canceling parcel post packages.

The primary object of my invention resides in the provision of a novel stamping means arranged in spaced relation with a support, the latter receiving the packages of the outgoing mail and which are adapted to be manually placed beneath the stamping means for facilitating the canceling of the stamps thereon.

Another object of my invention resides in the provision of a novel means for mounting the stamping means, the mounting means having resiliently supported thereon a novel inking means which is associated with the stamping means.

Another object of my invention resides in the provision of a novel means for imparting rotary motion to the stamping means for facilitating the canceling of a number of packages.

A still further object of my invention resides in the provision of a device of the character described that is simple in construction, efficient in operation and one that can be manufactured and placed on the market at a minimum cost.

Other objects as well as the nature, characteristic features and scope of my invention will be more readily understood from the following description taken in connection with the accompanying drawings and pointed out in the claim forming a part of this specification.

Referring to the drawings:—

Figure 1 is a side elevational view of my invention; and

Fig. 2 is a top plan view of the same applied to a portion of the support.

Referring more particularly to the drawings in which similar reference numerals designate like or corresponding parts throughout the different views, I provide a support, which in this instance consists of a table 1, the latter having a base plate 2 secured in close proximity to one side edge of the table and adjacent one end by means of suitable fastening devices preferably

bolts 3 and nuts 4. Formed integral with and extending upwardly from the base plate 2 is a vertical standard 5, the latter being 60 arranged perpendicular to the table 1 and has an arm 6 extending laterally from the upper end thereof, the arm being arranged in spaced relation to the vertical plane of the side edge of the table as clearly shown 65 in the drawings and has the extreme outer end thereof provided with an opening 7 for a purpose to be hereinafter described. In order to provide a lateral support for the arm, I have formed integral with the standard 5 and the arm 6 a diagonally extending brace 8.

Rotatably mounted in the opening 7 in the arm 6 is a stub shaft 9, the latter having a stamping wheel 10 rigidly mounted 75 thereon and arranged in spaced relation to the inner side of the arm 6, the wheel having a plurality of stamping plates 11 arranged in uniform spaced relation about the outer periphery thereof, each plate receiving 80 the name of the town from which the package is sent, and which plates 11 are arranged in suitable spaced relation with the table 1 to allow packages and the like of the outgoing mail to be placed beneath the 85 same by both hands of the clerk to facilitate the canceling of the stamp thereon.

In order to rotate the wheel and facilitate the stamping of the packages manually disposed beneath the plates 11 thereon I have 90 rigidly secured to the outer end of the stub shaft 9 a beveled gear 12, the latter being arranged in close relation with the side face of the wheel 10 and arranged in mesh with the beveled gear 13 rigidly mounted on the 95 free end of the horizontally disposed shaft 14, the latter being rotatably mounted in the spaced laterally extending bearing arms 15 formed integral with the side of the arm 6. The opposite end of the shaft extends beyond the support 5 and has a pulley 16 rigidly mounted thereon, the latter having a belt 17 operating thereabout which is in turn trained about a pulley 18 of the motor 19 which supplies power for rotating the 105 shaft 14 and consequently the shaft 9.

In order to thoroughly apply ink to the stamping faces of the plates 11, I provide a spring-like arm 20 and have secured one end of the same by means of a suitable fastening device 21 to the upper edge of the arm 6 adjacent the standard 5, the opposite end of the arm 20 being provided with an extension 22 which has its outer end bent and ar-

ranged in spaced relation with the free end of the arm and which extension and arm have rotatably mounted therebetween an inking roller 23, the latter, because of the arrangement of the extension 22, being positioned above the plates 11 carried by the stamping wheel 10. An arcuate guard 24 which conforms substantially to the outer periphery of the roller 23 is arranged in spaced relation with the roller and is rigidly secured to the upper face of the arm 20 by means of a suitable fastening device as clearly shown in the drawing and prevents the ink from being thrown about when the wheel 10 is being rotated. In order to hold the roller 23 in engagement with the plates 11, I have provided a leaf spring 25 and rigidly secured one end of the same by means of a suitable fastening device 26 on the upper edge of the arm 6 at a point above the standard 5, the free end of which spring bears against the arm 20 at a point adjacent the extension 22 and which at all times holds the roller 23 in engagement with the plates 11 and facilitates the inking of the same for canceling purposes.

The operation of my invention is as follows:—

Assuming that the motor is started by suitable controlling means, not shown, rotary motion is imparted to the horizontally disposed shaft 14 by means of the belt 17 and which motion is imparted to the stub shaft 9 by means of the beveled gears 12 and 13 which are arranged in mesh with each other. Because of the rigid connection between the wheel 10 and the shaft 9 when rotary motion is imparted to the shaft 9 the wheel 10 is rotated, whereupon the plates 11 coming in contact with the inking roller 23 which is held in engagement with the plates 11 by means of the spring arm 25, a suitable amount of ink is applied to the stamping faces of the plates 11 which plates engage the package or the like positioned on the table 1 and held beneath the wheel by the hands of the clerk so that the exact canceling of the stamp will be obtained when the wheel is rotated in the manner set forth. By this arrangement it can be seen that as soon as one package has been stamped another package may be engaged by the hands of the clerk and placed in position beneath the wheel while the same is being rotated which rotation causes the efficient canceling of the stamp and at the same time places the name of the town from which the package is sent on the package and the package can now be removed to allow another package being placed beneath the stamping wheel.

Although I have shown and described the preferred embodiment of my invention, I desire to be understood that I am not limited

to the exact details shown, however, great stress is laid upon the provision of a stamping means arranged in spaced relation with the support which receives the mailing packages and which are adapted to be placed beneath the wheel when the same is being rotated for canceling the stamps on the package. It can be seen that by this arrangement the clerk has the use of both of his hands for facilitating the correct stamping of the packages and in this manner saves a great deal of time as well as efficiently stamping the packages.

From the above description taken in connection with the accompanying drawings it can easily be seen that I have provided a device that is simple in construction containing but a few simple parts that can be cheaply manufactured and assembled and when assembled can be placed upon the market and sold at a minimum cost.

It will be understood that the above description and accompanying drawings comprehend only the general and preferred embodiment of my invention and that various minor changes in detail of construction, proportion and arrangement of the parts may be made within the scope of the appended claim and without sacrificing any of the advantages of my invention.

Having thus fully described my invention, what I claim as new and desire to secure by Letters Patent, is:—

A canceling machine for packages or the like, comprising, a standard to be secured upon a table, an arm laterally projecting from said standard for a predetermined distance, a disk rotatably supported on the free end of said arm and to be in spaced relation with said table, a gear on said disk a shaft rotatably supported on said arm and carrying a pinion to mesh with said gear on the disk, one end of said shaft being adapted to be connected to a driving means whereby said disk is rotated, a plurality of type characters mounted on the periphery of said disk in a substantially uniformly spaced relation, a substantially resilient arm secured to said lateral arm and having rotatably mounted thereon an ink supplying roller to engage with the type characters on said disk, and spring means engaging upon said resilient arm for holding said roller in constant engagement with the type characters on the disk with a predetermined pressure, substantially as and for the purposes set forth.

In testimony whereof I affix my signature in presence of two witnesses.

GEORGE M. CULLEN.
